CLAIM

The ornamental design for a door bin, as shown and described.

DESCRIPTION

FIG. 1 is a front bottom perspective view of the first embodiment of a door bin, showing our new design;

FIG. 2 is a rear bottom perspective view thereof;

FIG. 3 is a bottom plan view thereof;

FIG. 4 is a front bottom perspective view of the second embodiment of a door bin, showing our new design;

FIG. 5 is a rear bottom perspective view thereof; and,

FIG. 6 is a bottom plan view thereof.

The broken lines depict portions of the article that form no part of the claimed design.
